WELL-DRILLING RIG

Charlie E. Geiser, Artesia, N. Mex.

Application February 27, 1948, Serial No. 11,630

8 Claims. (Cl. 255—11)

1

This invention relates to improvements in well drilling rigs, particularly of the cable drill type adapted for drilling of oil and gas wells by a "spudding" operation.

Such prior spudders have been used heretofore, but they have involved complex structures in which the operating mechanisms are not compact, which has presented difficulties in operation, and also in the transportation of the equipment in moving it from well to well.

An object of this invention is to improve the construction of well drilling apparatus of the character described, by arranging the assembly into a compact unit that will be efficient for operation and transportation.

A further object of the invention is to improve the manner of controlling and operating the several power driven units of the apparatus, particularly the drums on which the cable is wound, to provide multiple sets of operations thereof, and effective control by clutches and brakes.

These objects may be accomplished by mounting the several cable drums in tandem relation within the frame of the spudder and locating the drive units, including the brake and control units laterally from the frame structure in a compact assembly which will be efficient for operation and may be moved without difficulty from well to well. The location of the clutch and brake units and the drive for the several cable drums, laterally with respect to the frame that encloses the drum but within the supporting frame, produces a compact machine effect and eliminates complex mechanism that has been required heretofore in such spudders, enabling the device to be manufactured at low cost and to be transported readily from well to well without substantial disassembly.

This embodiment of the invention is illustrated in the accompanying drawings, in which:

Fig. 1 is a side elevational view of the drilling apparatus;

Fig. 2 is an elevational view of the opposite side thereof;

Fig. 3 is a top plan view thereof;

Fig. 4 is a horizontal sectional view showing parts of the assembly in plan, taken on the line 4—4 of Fig. 1;

Fig. 5 is a front elevational view of the drilling apparatus;

Fig. 6 is a vertical cross sectional view taken on the line 6—6 of Fig. 1;

Fig. 7 is a perspective view of the drilling and reverse clutch, shown removed from the drilling apparatus;

Fig. 8 is a perspective view of one of the cable guide pulley blocks;

2

Fig. 9 is a vertical cross section on the line 9—9 of Fig. 1;

Fig. 10 is a fragmentary side elevational view, partly in section of the clutch and brake mechanism for the sand reel;

Fig. 11 is a fragmentary perspective view of the bell crank and shifter mechanism for the sand reel clutch;

Fig. 12 is a cross sectional view taken on the line 12—12 of Fig. 1;

Fig. 13 is a cross sectional view taken on the line 13—13 of Fig. 1;

Fig. 14 is a fragmentary view, partly in section to illustrate the spudder cross header and spudding sheave and shock absorber in locked position;

Fig. 15 is a cross sectional view taken on the line 15—15 of Fig. 14;

Fig. 16 is a view similar to Fig. 14 but with the lock cap removed and with the spring partially compressed to show the shock absorbing action, and;

Fig. 17 is a cross sectional view taken on the line 17—17 of Fig. 16.

25 The well drilling apparatus or spudder shown as one embodiment of this invention comprises an open frame construction, including pairs of longitudinal sills 1 and 2, at each opposite side of the frame extending in side-by-side relation and connected through cross sills 4.

30 Connected with the sills 1 and 2, at one end of the frame, is an axle 6, on which wheels 8 are mounted for supporting that end portion of the frame during transportation and also during operation, if desired, although it is preferred that the opposite ends of the frame be supported on blocks shown at 10 and 12, during the operation of the rig.

35 Upstanding from the sills 1 and 2 and the cross sills 4, at opposite ends of the rig are posts 14 and 16. Intermediate the opposite ends of the frame are standards 18, spaced at intervals both longitudinally and transversely of the frame to support thereon girders 20 and 22, arranged in pairs at each opposite side of the frame over the sills 1 and 2, as shown in Fig. 9. The girders 20 and 22 are connected together at the opposite ends of the frame by cross beams 24. These girders and beams form the supporting frame for the operating parts of the spudder, while the sills and standards described above, form the subframe thereunder. The parts of these frames are securely fastened together and braced to provide a rigid structure, capable of withstanding the conditions of operation that may be encountered in service.

At one end of the structure is supported a frame 26, upon which a source of power is adapted to be provided, such as an internal combustion engine 28. Any suitable power unit may be used, as desired, but the engine 28 is shown as connected through a belt drive 30 with a jack shaft 32, journaled in bearings 34 on the post 14.

Also supported on the diagonal braces between the standards 14 and 18 and the frame 20—24 is a shaft 36, which shaft is journaled in bearings 37. Shafts 38 and 40 are journaled in suitable bearings 39 and 41, respectively, on the frame, which shafts extend transversely from side to side, as shown in Fig. 3. These shafts support drums designated, respectively, at 42, 44, and 46. The drum 42 is of the character known as the sand reel drum and is journaled free on the shaft 36, for turning movement relative thereto, except when connected by clutch engagement as herein-after described. The drum 44 is the drilling drum and is keyed to the shaft 38 to turn therewith. The drum 46 is the calf wheel or casing drum and is journaled for free turning movement on shaft 40.

The opposite ends of the shaft 40 have fixed thereon cranks 43 connected through pitmans 50, with spudding arms 52, being pivoted thereto at 54. The spudding arms 52 extend lengthwise of the frame structure, as shown in Figs. 1 and 2, and are pivotally mounted on the upper ends of the post 14 by a cross rod 56. The free ends of the spudding arms 52 are secured in rigid relation by a tubular connecting rod or header 53.

The mast is shown at 58, in the form of a rectangular frame structure as illustrated in Figs. 1 and 5, the lower end of which includes a cylindrical base member 60 adapted to be engaged in seats 62 in the projecting ends of the sill 2. This structure forms a detachable mounting for the mast, whereby it may be supported in proper position over the well or be removed therefrom during transportation. The upper end of the mast 58 carries a mast head, generally designated at 64, having sheaves 66 adapted to receive the respective lines, such as the sand line 68 from the drum 42 or the drilling line 70 from the drum 44, and the casing line 71 from the drum 46. The mast 58 may be anchored in its set position by guy lines 59.

The sand line 68 is shown as extending from the drum 42 over a pulley block assembly, generally designated at 72, and shown more in detail in Fig. 8. This assembly includes a sheave 74, journaled at 76, in one end of a frame 78. In the opposite end of the frame 78 is mounted a guide roller 80, journaled therein at 82, in position to engage and ride upon the rod 56, to permit the sand line 68 to travel back and forth on the drum 42. The frame 78 may be of any fabricated structure capable of holding the sheave and pulley in proper relation.

The drilling line 70 extends from the drum 44 over a sheave 84 of a pulley block assembly 86, as shown in Fig. 1. The unit 86 is the same in construction as the pulley block assembly 72, described above and illustrated in Fig. 8. The pulley block assembly 86, preferably has two pulleys 83 and 84 positioned at right angles to each other. Such a pulley block assembly allows a rolling action of pulley 83 along rod 85 to permit the cable 70 to be evenly spooled upon drum 44. By having the pulleys 83 and 84 mounted at right angles to each other and pivoted on their respective axes, the pulley 84 will automatically align with the cable 70 as it comes from the spudding sheave 88.

The pivotal mounting of the pulleys permits angular movement thereof relative to rod 85 so that said pulleys will align with the sheave 88 to properly guide the cable 70 onto the winding drum 44.

A rod 87 is provided to support the weight of the pulley block assembly 86 when the line 70 is not in tension, however, when the line 70 is in tension, the pulley block assembly will be lifted clear of the rod 87.

From the sheave 84, the drilling line 70 extends about a sheave 88 carried by the header 53 on the spudding arms 52, and shown more in detail in Figs. 14—17. From the sheave 88, the line extends over one of the sheaves 66 on the mast 58, thence to drilling tools in the well. The drill, supported by the line 70, is adapted to be raised and lowered as the spudding arms 52 rock vertically.

The sheave 88 is carried by a yoke 90, in which it is journaled, and which yoke is pivotally connected at 92 to the upper end of eye-bolt 94, that extends downwardly through the connecting header 53 of the spudding arms 52. The bolt 94 extends through a sleeve 96 in the tubular connecting rod or header 53, the lower end of which sleeve 96 is open and slidably receives therein a plate 98, slidably mounted on the bolt 94 and confined by nuts 100. A coiled spring 102 is interposed between the plate 98 and the closed upper end of the sleeve 96. In order to relieve the drilling machine of shock, yieldable action is provided for the sheave 88. When sufficient depth is reached that the cable has sufficient stretch or elasticity to compensate for the shock, the cap 106 may be secured to the bolt 94 by nuts 108 and the sheave 88 then becomes rigid with respect to connecting header 53, as shown in Figs. 14—17. It is to be pointed out that no disassembly of parts is necessary in order to eliminate the shock absorbing feature, and by the removal of nuts 108 and cap 106, the shock absorbing feature is put back into function in a few minutes time.

The shaft 36 is shown as provided with cat heads 110, on opposite ends thereof which may be used, if desired, upon power operation of the shaft.

The parts are driven from the jack shaft 32, operated by the power plant or engine 28, as described above. The jack shaft 32 has a pulley 112, on one end thereof, in the form illustrated, and may be provided with clutches 114 and 116 for connecting the jack shaft 32 to the pulley 112, if desired. These forward and reverse clutches 114 and 116, respectively, may be of the well known construction adapted for alternate engagement, according to the movement of a clutch control lever connected therewith for forward or reverse operation by lever 117. The lever 117 is adapted to operate clutches 114 and 116 by forward and reverse movement thereof. At a midpoint between the engagement of the respective clutches is a disengaged or neutral position for lever 117. Upon movement of clutch lever 117 in one direction, the rod 117a is moved in the same direction. The rod 117a actuates a three-way bell crank lever 117b. This causes clutch 114 to be engaged by movement of lever 117c which causes turning movement of pulley 112 in one direction. Upon the reverse movement of lever 117 and rod 117a the bell crank 117b through the lever 117c will move in the opposite direction to cause disengagement of clutch 114, and upon further movement will enter a position and by continued movement in the same direction will move the clutch mechanism to cause a gripping action of friction clutch band 117d and through planetary gears within

the clutch, will cause a reversal of pulley 112 with respect to jack shaft 32.

The pulley 112 is adapted to be connected through V-belts 119 and 121 with pulleys 118 and 120, of different sizes, which latter pulleys are mounted on the shaft 36 for operating this shaft. The respective pulleys 118 and 120 are adapted to turn free on the shaft 36 but to be connected with the shaft by clutches 122 and 124, respectively, whereby to operate the shaft at different speeds according to which of the clutches 122 or 124 is engaged. These clutches 122 and 124 are adapted to be controlled by a rod 126 (Fig. 4) extending therefrom to a control lever 128 for alternate engagement.

The sand reel drum 42, Figs. 9 and 10, which is also journaled free on the shaft 36, may be connected therewith by a clutch 130 to rotate with the shaft when desired.

The shaft 36 carries a drive pulley 132, shown as connected through V-belts 134, with a band wheel 136 journaled freely on the shaft 40. The band wheel 136 may be coupled with the shaft 40 by a clutch 138 to rotate the shaft, inasmuch as the band wheel is power driven through V-belts 134 from the jack shaft 36. Upon operation of the shaft 40, the cranks 48 and pitman 50 will be operated to rock the spudding arms 52.

The band wheel 136 is shown as connected through a sprocket 139, and through chain 140, with a sprocket wheel 142, journaled free on the shaft 38, but coaxial therewith. A clutch 144 is adapted to connect the sprocket wheel 142 with the shaft 38, so as to drive this shaft and the drilling drum 44 when desired, upon operation of the band wheel 136. The drilling drum 44 is shown also as provided with a brake unit 146 connected with the shaft 38 to control the operation thereof.

The drilling drum 44 is securely keyed to shaft 38, as is the brake friction drum 145 so when drum 44 rotates the brake friction drum 145 will rotate in unison therewith. A brake band 143 is provided to partially encircle brake friction drum member 145, which brake band is anchored to a rod 146a extending between side sills 1 and 2. The opposite end of the brake band is connected to one end of a bell crank 146b. The other end of the bell crank 146b is connected to a brake rod 146c which extends forward and is connected with a lever 146d within easy reach of the operator.

The casing drum 46 is journaled free on the shaft 40, but is adapted to be connected therewith by means of a clutch 148. The casing drum 46 has a pair of brake bands 147 adapted to be anchored to a rod 147a extending between sills 2. The opposite ends of the brake bands are connected to a lever 147b which is connected to a shaft that is keyed to operating lever 147d in position to be operated by the operator.

As shown in Fig. 4, the drums 42, 44, and 46 are mounted on the respective shafts between the beams 22 of the supporting frame, while the drive provisions for the respective shafts and the controls of the shafts are located between the beams 20 and 22, at each opposite side of this frame. This has the effect of better control of the respective drums and the winding shafts thereof, and it also provides for arranging the rig in a more compact, practical manner, and also gives a stronger framework.

While the respective clutches described may be operated in any suitable manner, I have shown in Fig. 4, a series of control rods extending there-

from to a control position at the front end of the rig, where an operator may have access to a series of control levers therefor. As mentioned above, the clutches 122 and 124 are operated by a control lever 128, which lever is adapted to rotate rod 126 through an arcuate movement, which in turn shifts clutch levers carrying yokes 150 and 151 to operate clutches 122 and 124, respectively.

These clutches are preferably of the friction type, although any suitable clutch, whether positive or friction, may be used as desired. By having the clutches 122 and 124 operable by a single lever 128, either of the clutches may be disengaged, and by movement of the lever 128, with the lever shifted through neutral or disengaged position, the other clutch may be shifted into engagement without having to change to a different lever to accomplish the desired result. Furthermore, by having clutches arranged in this manner, and by providing clutches of the friction type, the shifting of the clutches which will effect a change in ratio of speed with respect to the drive member, enables the speeding up of the drum 42 or the slowing down thereof for greater pulling power, without loss of the momentum established while in the other speed. In a similar manner, the clutches 138, 144 and 148 are controlled from the operating position of the rig. The clutch 138 has a link 152 connected with a shaft 154 extending to a control lever 156. The clutch 148 has the yoke 149 thereof connected by a link 158, with a shaft 160 that is shown as provided with a foot pedal 162, as shown in Fig. 13. The clutch 144 has the yoke thereof connected through a link 164 with a shaft 166 provided with a control lever 168. These clutches may be operated selectively to provide the desired operating connections for the rig.

The clutch 130 for controlling the sand reel or drum 42 has an operating yoke 170 connected therewith, as shown in Fig. 9, for shifting the clutch. The yoke 170 is connected with one side of a bell crank lever 172, as shown in Figs. 10 and 11, from which a shift rod 174 extends to a control lever 176.

Also associated with the sand reel or drum 42 are brake bands 178, as shown in Figs. 9 and 10, extending about the flanges of the drum. One end of each of the brake bands 178 is anchored at 180, as shown in Fig. 10, while the opposite end thereof is connected with one arm of bell crank lever 182, the other end of which is attached to a link 184 which extends to a rocking member 186, having a bifurcated upper end that is in position to be actuated by the lever 176. A spring 188 is connected with the link 184, normally tending to move the latter to release the brake bands 178, and move bifurcated lever 186 against stop pin 190. The rocking member 186 is so disposed with respect to the lever 176 that, upon disengagement of the clutch 130, the movement of the lever 176 in a direction to disengage the clutch will actuate the rocker member 186, to apply friction to the sand reel or drum 42, by brake bands 178, for stopping the free turning movement of this drum on the shaft 32.

The apparatus is adapted for use in the customary manner of operating a spudder either to cause a drilling action of the tool by the rocking action of the spudding arms 52, or to raise or lower the respective lines relative to the well. The mounting of the guide block assemblies 72 and 86, facilitates the action of the cables in the even winding on or the even unwinding from the respective drums.

It will be evident from the foregoing description, that the sand reel drum 42, drilling drum 44, and casing drum 46 arranged between the inner sills 2 of the frame work of the rig, in tandem relation, and are journaled on shafts 36, 38 and 40, respectively. Furthermore, it is to be pointed out that the sand reel shaft 36 forms a countershaft with dual speeds through which power is transmitted to pulley 132 which drives the band wheel 136.

The shaft 40 has a band wheel 136 journaled thereon but engageable therewith by engagement of clutch 138. The casing drum 46 is also journaled on shaft 40 and is engageable therewith by a clutch 148. This shaft 40 performs the triple functions of, first, supporting the band wheel, which in turn, will rotate sprocket 139 secured integral with band wheel 136 and which sprocket is adapted to drive sprocket 142 through chain 140. If the clutch 144 is engaged, shaft 38 of the drilling drum 44 will be driven to raise or lower the drilling tools within the well. And, secondly, if the clutch 144 is not engaged, and the clutch 138 is engaged, the shaft 40 will be driven, which will rotate cranks 48 disposed on either end thereof, so as to operate spudder arms 52 through pitmans 50. Third, when it is desired to operate the casing drum 46, the pitmans 50 are usually removed from the cranks 48, and the clutch 148 is engaged with the drum 46 on which cable may be spooled, and which cable is adapted to pass over one of the sheaves 5 to raise or lower the casing within the well.

The sand reel drum 42 is journaled on shaft 36 and is engageable therewith by clutch 130. It is desirable to have a sand reel that will operate at high speeds for light loads, and at slow speed for heavier loads. The sand reel has been placed upon the shaft 36, which normally would be a separate and independent shaft, however, this same shaft serves as a clutch shaft, so as to obtain the high and low speeds as desired, and obviates the necessity of additional shafts on which to mount the drum and other mechanism.

The particular clutch arrangement of the forward drive clutch 114, reverse drive clutch 116, low speed clutch 122 and high speed clutch 124, makes possible two speeds of the clutch or sand reel shaft 36 to be had in each direction, which gives great versatility to the operation of the machine to adapt it to a specific job at the correct speed.

The motor drive unit 28 may be provided with a transmission and clutch 29, if so desired, which will give additional speeds thereto.

Control levers 117, 128, 146d, 147d, 156, 162, 168 and 176 are provided, within easy access to the operator of the machine, for controlling the operation of the various functions of the drilling apparatus. The lever 117 serves the dual function of operating the forward and reverse movement of the clutches 114 and 116. The lever 176 serves the dual purpose of operating the engagement and disengagement of clutch 130 and engagement and disengagement of brake bands 178 on sand reel 42.

Engine power unit 28 is shown as having V-belt pulleys 31 driving through V-belts 30 to a drive pulley 33 on jack shaft 32.

The lever 128 serves the dual purpose of engaging and disengaging clutches 122 and 124. From the foregoing description, it can be readily appreciated that the amount of mechanism required to build and operate the rig has been materially reduced, thus simplifying the construction and

operation of the drilling rig. By the reduction of the number of controls and the reduction of the number of drives and shafts incident thereto, a substantial saving in the weight of the machine is to be had. The reduction of the number of working parts makes for easier and more efficient operation of the machine and for the same reason, wear and replacement is greatly reduced.

Additional features that are provided for in this rig that have not been found in such rigs heretofore, are cable spooling guide sheaves 74 and 84 which are free to move transversely on shafts 56 and 85 in accordance with the normal spooling action of the cable, which also have pivotal action to permit alignment with the cable.

Furthermore, a shock absorbing feature for the sheave 88 has been provided, as shown in Figs. 14-17, inclusive, and which may be locked out by a cap 106 and nuts 108 when the drilling has acquired sufficient resiliency and to make the shock absorbing feature unnecessary, which is usually at from 1000 to 1200 feet.

I claim:

1. In well drilling apparatus, the combination of a supporting frame comprising laterally spaced pairs of spaced beams, a plurality of shafts mounted on the frame, drums carried by the shafts between the pairs of beams, driving means connected with one of the shafts between the beams of one pair, driving means connecting the first-mentioned shaft with another of said shafts and located between the beams of another of said pairs of beams, clutches for connecting the driving means with the respective shafts, manual control means for the clutches extending to an operating position externally of the frame, a spudder arm, means for operating the spudder arm from one of said shafts, a sub-frame including upright posts and supporting said supporting frame, and means mounting the spudder arm on at least one of the upright posts.

2. In well drilling apparatus, the combination of a supporting frame comprising laterally spaced pairs of spaced beams, a plurality of shafts mounted on the frame, drums carried by the shafts between the pairs of beams, driving means connected with one of the shafts between the beams of one pair, driving means connecting the first-mentioned shaft with another of said shafts and located between the beams of another of said pairs of beams, clutches for connecting the driving means with the respective shafts, manual control means for the clutches extending to an operating position externally of the frame, a spudder arm, means for operation of the spudder arm from one of said shafts, a sub-frame including sills and having the supporting frame mounted thereon, a pair of said sills having seats in the upper faces thereof, and a mast mounted in the seats and supported thereby adapted to form a guide for a line from at least one of the drums.

3. In well drilling apparatus, the combination of a supporting frame comprising spaced pairs of spaced beams, a plurality of shafts mounted on the frame, one of said shafts being an intermediate shaft, drums carried by the respective shafts, power means connected with one of the shafts between the beams of one pair, driving means connecting said shaft with said intermediate shaft and located between the beams of the other pair, driving means connecting said intermediate shaft with another of said shafts and located between the beams of said other pair, clutch means for controlling the connection of

said driving means with the respective shafts, a spudder arm, and means connected with said intermediate shaft for operating said spudder arm.

4. In well drilling apparatus, the combination of a supporting frame comprising pairs of spaced beams, a driving shaft, an intermediate shaft and a driven shaft mounted on said frame, rotatable drums on said driving shaft and said intermediate shaft, a drum fixedly mounted on said driven shaft for rotation therewith, power means connected with said driving shaft between the beams of one pair, driving means connecting said driving shaft with said intermediate shaft and located between the beams of the other pair, driving means connecting said intermediate shaft with said driven shaft and located between the beams of said other pair, clutch means for selectively controlling the connection of said driving means with the respective shafts, clutch means on said driving shaft and said intermediate shaft respectively for connecting said rotatable drums to said shaft for rotation therewith, a spudder arm, and means connected with one of the shafts for operating said spudder arm.

5. In well drilling apparatus the combination of a frame structure comprising pairs of horizontally spaced beams spaced apart, a plurality of shafts mounted on the frame, at least one of said shafts being supported on all of said beams, reels carried by the shafts between the pairs of beams, power driving and controlling mechanism for the shafts located between the beams of at least one pair, a spudder arm, and means actuated by one of said shafts for operating the spudder arm.

6. In a portable well drilling apparatus having winding drums and a spudder arm, the combination of a supporting frame comprising four vertical pairs of transversely spaced longitudinal beams, winding drums carried by shafts, which shafts are mounted between the two upper central transversely spaced longitudinal beams, power transmission means positioned between the outer pairs of said transversely spaced longitudinal frame members for selectively driving the respective winding drums mounted on said shafts, power means connected to one of said shafts and clutch means for selectively connecting said power means with said respective winding drums for rotation thereof, and further clutch means for selectively connecting said spudder arm with said power means.

7. In a drilling rig, the combination of a supporting frame comprising laterally spaced pairs of spaced beams, a bearing on each of said beams which bearings are axially aligned, a shaft 55 journaled in said bearings, a winding drum

journaled on said shaft between the beams of one pair of said laterally spaced pairs of beams, gear means journaled on said shaft and positioned between the beams of another pair of laterally spaced pairs of beams, clutch means on said shaft for connecting said gear means in driving relation with said shaft, and further clutch means on said shaft for connecting said winding drum in driven relation therewith.

8. In a drilling rig the combination of a supporting frame comprising laterally spaced pairs of spaced beams, a bearing on each of said beams which bearings are in axial alignment, a shaft journaled in said bearings, a crank on each end 10 of said shaft and secured thereto exterior of each outermost beam, spudder arms mounted above said beams for arcuate movement, connecting means interconnecting said spudder arms with said cranks to move said spudder arms through 15 said arcuate movement upon rotation of said cranks mounted on said shaft, a winding drum journaled on said shaft between the beams of one pair of said pairs of laterally spaced beams, a band wheel journaled on said shaft and positioned between the beams of another pair of said laterally spaced pairs of beams, a clutch means 20 on said shaft for connecting said band wheel with said shaft, and further clutch means on said shaft for connecting said winding drum in driven 25 relation therewith.
